UNITED STATES PATENT OFFICE.

ELLEN DUNWOODY NESTER, OF GARDNER, MASSACHUSETTS.

CHILD'S CLOTHING.

1,424,318.

Specification of Letters Patent. Patented Aug. 1, 1922.

Application filed February 23, 1922. Serial No. 538,586.

To all whom it may concern:

Be it known that I, ELLEN DUNWOODY NESTER, a citizen of the United States, residing at Gardner, in the county of Worcester and State of Massachusetts, have invented certain new and useful Improvements in Children's Clothing; and I do hereby declare the following to be a full, clear, and exact description of the invention, such as will enable others skilled in the art to which it appertains to make and use the same.

This invention relates to children's clothing made in one piece and devoid of buttons and has for its object to provide a single piece garment which will be comparatively inexpensive to manufacture and more useful and efficient in use than those that have been heretofore proposed.

With these and other objects in view, the invention consists in the novel details of construction and combinations of parts more fully hereinafter disclosed and particularly pointed out in the claims.

Referring to the accompanying drawings forming a part of this specification:

Figure 1 illustrates the one piece garment in use on a child;

Figure 2 is a view from the rear of the one piece garment spread out; and

Figure 3 is a fragmentary sectional view showing a portion of the rear and of the front of the garment.

1 indicates a blouse which may be made of any suitable material and which is provided with a back portion 2 and a front portion 3. The back portion of the blouse is provided with a rear edge 4 which is or may be of the usual construction of blouses, but its front portion 3 is provided with an extension 5 which when spread out as illustrated in Figure 2 may be as long as from the arm pits to the rear edge 4 or it may be of any other dimensions desired.

To the lower portion 6 of said extension 5 is secured through an arc of say about 180° the waist band 7 of a pair of bloomers 8, so that the blouse 1, extension 5 and bloomers 8 are all in one piece. The waist band 7 of the bloomers is preferably gathered as illustrated at 9 and in said waist band is located an elastic band 10 which grips the waist of the child and thus holds the bloomers in place when they are lifted from the

position shown in Figure 2 to the position 55 shown in Figure 1.

In other words, referring more particularly to Figure 3, the front portion of the blouse proper may be said to extend down to the folding line 11 when the extension 5 begins. The said extension continues down to the waist band 7, and when the bloomers are in position on the child they are raised so as to produce the line of fold 11 which is on the same horizontal plane as the rear edge 4 of the back 2 of the blouse.

Stated in still other language, the appearance of the garment on the child is of a two piece suit whereas the real construction is a one piece suit devoid of buttons. 70

In order to make a more slightly garment, the front portion 3 may be extended somewhat more than 180° around the child. That is to say, the seams 14 connecting the front portion 3 with the rear portion 2 of the blouse, instead of being located at 180° apart may be carried over somewhat on the back portion 2 to provide the folded portions 15 and 16 of the cloth, which when the bloomers 8 are raised into the position 80 shown in Figure 1, cause the material to drape more gracefully than would be the case if the seams 14 were strictly 180° apart. On the other hand, of course, if it is desired to have the rear edge of the blouse 85 and the front edge 11 thereof of exactly the same length such a construction may be adopted.

It will thus be seen that by providing the construction disclosed, I am enabled to 90 produce a one piece suit which is devoid of buttons. Further, when placing the suit on the child it is only necessary to have the child step into the bloomers 8 and to slip the blouse over the child's head, when the 95 bloomers may be pulled up into the position shown in Figure 8, when the elastic 10 holds the latter in place.

It is obvious that those skilled in the art may vary the details of construction as well 100 as the arrangement of parts without departing from the spirit of the invention, and therefore I do not wish to be limited to the above disclosure except as may be required by the claims.

What I claim is:

1. A one piece buttonless suit comprising a blouse and a pair of trouser members, one

side only of the blouse provided with a continuous extension; said trouser member permanently connected with the extremity of said extension only and said extension adapted to be folded to form a lower edge of said blouse when the trouser members are in position on the wearer, substantially as described.

2. A one piece buttonless suit comprising a blouse member and a pair of trouser members, the blouse member provided with an extension permanently connecting the trouser members therewith which is folded to form a portion of the lower edge of the blouse when the trouser members are in use on the wearer, and said trouser mem-

bers provided with a waist belt adapted to hold them in place, substantially as described.

3. A child's one piece buttonless suit comprising a pair of bloomers and a blouse with the usual rear lower edge and a front portion having an extension permanently connected with said bloomers, said extension being folded to form the front lower edge of the blouse when the bloomers are in their wearing position on the child, and said bloomers provided with an elastic waist band to hold them in place, substantially as described.

In testimony whereof I affix my signature.

ELLEN DUNWOODY NESTER.
